UNITED STATES PATENT OFFICE.

JAMES G. MACLAREN, OF SYRACUSE, NEW YORK, ASSIGNOR TO THE LAMSON COMPANY, OF SYRACUSE, NEW YORK, A CORPORATION OF MASSACHUSETTS.

POWER CONTROLLER.

Application filed March 26, 1926. Serial No. 97,562.

This invention pertains to pneumatic despatch system of the so-called "minimum flow" vacuum type and relates more particularly to automatic power controlling apparatus for use in such a system.

Power control apparatus of this general character is disclosed in the patent to Libby No. 968,576, dated August 30, 1910. The patented apparatus provides automatic pressure actuated means for initiating a carrier impelling air flow through the transmission tube whenever a carrier is entered therein as well as means for cutting off such flow after the lapse of a predetermined period of time. While I regard the patented device as generally correct in principle and highly effective in practice, I believe it preferable to have the cessation of carrier impelling air flow depend directly upon the discharge of the carrier from the delivery end of the tube rather than upon the operation of a timing device, and the principal object of this invention is to provide an improved power control apparatus comprising means actuated automatically upon insertion of a carrier within the despatch terminal to initiate flow of the air propelling current and also operating automatically when the last carrier emerges from the delivery terminal to cut off the air current abruptly.

In the accompanying drawings I have disclosed one preferred embodiment of the invention by way of example;

Fig. 1 being a fragmentary elevation illustrating part of the central station desk of a pneumatic despatch system having the improved power control apparatus applied thereto;

Fig. 2 is a vertical section to larger scale through the casing of the improved power control apparatus showing the several parts in the position which they assume when the transmission tube is empty;

Fig. 3 is a view similar to Fig. 2 but showing the parts in the position which they assume immediately after a carrier has been inserted in the transmission tube;

Fig. 4 is a similar view showing the parts in the position which they occupy soon after flight of the carrier has been initiated but before the carrier discharges;

Fig. 5 is a similar view showing the parts

in the position which they occupy at the instant after discharge of the last carrier from the transmission tube;

Fig. 6 is an elevation looking from the left hand side of Fig. 4;

Fig. 7 is an elevation, partly in section, looking from the right hand side of Fig. 4;

Fig. 8 is a fragmentary front elevation of the control apparatus, certain parts being broken away and in section;

Fig. 9 is a fragmentary vertical section substantially on the line 9—9 of Fig. 2;

Fig. 10 is a fragmentary detail view similar to Fig. 2 but illustrating a modification; and

Figs. 11 and 12 are fragmentary sectional views illustrating further modifications.

Referring to the drawings, the numeral 1 indicates a fragmentary portion of the central station desk of a pneumatic despatch system comprising transmission tubes, such, for example, as the tube 2, which lead from the central station desk to remote sending or clerks' stations. Each tube is furnished with a delivery terminal 3 and is provided with a continuation 4 connecting it to the casing 8 of an individual power control device indicated generally by the numeral 5. This power control device is connected in turn by means of a suction tube 7 to a vacuum drum or header 9 in which a low pressure is continually maintained by means of a suitable pump, exhauster, or equivalent apparatus not shown.

An open-ended despatch terminal 6 is provided at the central station for each of the transmission tubes 2, such despatch terminal forming the entrance to that run of the tube which leads to the corresponding remote sending station. The above arrangement in general is old and well known in this art, and further details of such general arrangement are, therefore, unnecessary, the present invention being confined to improvements in the power control apparatus per se.

The improved power control apparatus as herein disclosed comprises a hollow casing 8 having suitable openings at its top and bottom for the reception of the ends of the tubes 4 and 7 respectively, and preferably has a removable door 8^a covering an aperture in its wall. This casing is divided by an in-

ternal septum 10 into an inlet chamber 11 communicating with the tube 4 and an outlet chamber 12 communicating with the tube 7. The septum 10 is provided with a large valve 5 aperture 13 of sufficient capacity to permit full carrier impelling air flow to pass from the chamber 11 to the chamber 12.

The side wall 14 of the casing 8 is furnished with an outstanding annular flange 16 forming a seat for the margin of a flexible diaphragm 17 hereinafter referred to under the broad term "pneumatic." The casing also comprises a removable dished cover member 18 having a flange 19 which clamps 15 the edge of the diaphragm against the seat 16. This cover may be held in position by bolts or in any other suitable manner. The space 15 between the wall 14 and the diaphragm communicates freely with the inlet chamber 11 by means of an orifice 21, while the space 22 between the diaphragm and the cover member 18 normally communicates with the outer atmosphere by means of a port 23.

25 The cover 18 is provided with an outstanding lug or bracket 24 providing a pivotal support for a lever 25 which supports an auxiliary valve 26 adapted at certain times to close the port 23 and thus to cut off 30 communication between the chamber 22 and the outer atmosphere. Preferably the lever 25 is extended beyond its pivotal support to provide an arm carrying a counterweight 26a.

35 The chambers 15 and 22 communicate at all times by means of a restricted passage 27 controlled by a needle valve 28. This needle valve may be adjusted from the outside of the casing and determines the rate of flow 40 of air from one side of the diaphragm to the other.

The cover 18 is preferably provided with a central boss 29 having a guide opening therethrough and the wall 14 of the casing is furnished with a thickened part 30 having a guide opening aligned with the opening in the boss 29. A stem rod, or valve actuating element 31 slides freely in the openings in the parts 29 and 30. This stem is fixedly secured to the central part of the diaphragm by means of a suitable clamping device 32. The stem projects outwardly beyond the cover 18 and is encircled by a compression spring 33 bearing at one end against the boss 29 and at its other against an abutment member 34 which is held in adjusted position on the stem by means of a nut 35 engaging the screw-threaded outer end of the stem. By adjusting this nut the tension of the spring 33 may be varied, the spring tending at all times to maintain the diaphragm in the position shown in Fig. 2.

60 A bracket 36 is adjustably mounted upon the outer end of the stem 31 by means of suitable adjusting nuts 37. A light tension

spring 38 is attached at one end to the bracket 36 and at its other to a pin 38a projecting from the end of the lever 35. These parts are so proportioned that when the diaphragm occupies the position of Fig. 2 the auxiliary valve 26 will also occupy the position shown in Fig. 2 unless forcibly held in another position as hereinafter described.

The inner end of the stem 31 is furnished with a stop collar 39 adapted to abut the member 30 and to limit outward movement of the stem by the spring 33. The inner end 40 of the stem is normally disposed closely adjacent to the under surface of a pivoted controlling valve 41 which governs the flow 45 of air through the aperture 13 and which is supported at its lower end upon a shaft 42 journaled at its opposite ends in the walls of the casing. The valve is fixedly secured to this shaft in any desired manner, and the valve may be of any suitable construction, but is preferably of sheet metal reinforced by ribs or otherwise to make it sufficiently stiff.

The shaft 42 projects beyond the front 50 wall of the casing (Figs. 9 and 10) and is encircled by a coiled spring 43 of clock spring type, the inner end of which is attached to a sleeve 44 adjustably secured to the shaft 42 by means of a set screw 45. The outer end of the spring 43 is anchored to a post 46 projecting from the wall of the casing. Preferably the spring is enclosed by a cap or cover 47 having slotted ears 48 engaging set screws 49 projecting from the wall of the casing 8. By loosening these screws the cover may be removed to expose the spring for repairs or for adjustment of its tension. This latter may be accomplished by loosening the set screw 45 and turning the sleeve 44 relatively to the shaft 42.

For protecting the auxiliary valve 36 and the parts associated therewith I prefer to provide the cover 18 with a hollow cap 18a 65 removably secured in position in the same way as the cap 47 just described, the cap 18a being provided with an opening 18b preferably aligned with the end of the stem 31 and adapted to allow free entrance of air 70 to the space within the cap.

The valve 41 is furnished with a downwardly directed toe 50 which engages the end of an adjusting screw 51 when the valve is in closed position. This screw is normally so adjusted that when the valve is in closed position it is spaced a short distance from its seat at the edge of the orifice 13, thus permitting a small flow of air from the chamber 11 to the chamber 12. This small flow constitutes the "minimum flow" so-called. If preferred, this minimum flow may be provided by means of an opening through the lower part of the septum 10 or by a pipe exterior to the casing connect- 130

ing the chamber 11 with the suction tube, but I prefer the present arrangement since it permits adjustment of the minimum flow from the exterior of the casing in a very simple manner.

The toe 50 is furnished with a contact portion 52 which, when the valve is closed as shown in Fig. 2, is disposed to the left of the vertical plane through the pivotal axis 10 of the valve 41. When the controlling valve is closed this contact element 52 bears against a latch spring 53 secured to the bottom wall of the casing and which may be adjusted by means of a screw 54. The coiled spring 43 is so tensioned that it tends to open the valve 41, but when the valve is closed as shown in Fig. 2 the differential air pressure at opposite sides of the valve is normally sufficient to keep the valve closed until some positive force is applied for opening it. The latch spring 53 is so adjusted that when the exhauster is shut down the spring 43 will not throw the controlling valve open. While the latch spring is desirable for the reasons just stated, it is not essential to the normal operation of the device.

When the valve 41 is open, it engages the inner end of a stop screw 55 adjustable from the outside of the casing. This screw is so adjusted that when the valve is wide open it stands in an inclined position with its free edge directed toward the oncoming air current. Tension of the spring 43 is such that it holds the valve in this open position after having been opened during the flight of the carrier and in opposition to the force of the flowing air current acting upon the upper or left hand side of the valve as viewed in the drawings.

40 In Fig. 10 a slight modification of the apparatus is disclosed, and in this figure 31^a designates the valve stem having the stop collar 39^a mounted thereon. The controlling valve 41^a is provided on its under surface 45 with a latch finger 56 adapted to engage the toe 57 of a latch lever pivoted at 58 and provided with a counterbalance 59. This latch lever is also furnished with an arm 30 engageable by the collar 39^a so that as the stem 31^a is moved to the left the latch lever is swung, thus disengaging the member 57 from the member 56 and permitting the valve to open.

50 In the modified arrangement shown in Fig. 11 the toe 52^b of the valve 41 is so shaped that when the valve is wide open a flat surface of the toe bears against the spring 53 thus assisting or replacing the spring 43 for holding the valve open.

55 In Fig. 12 a modified arrangement for adjusting the tension of spring 43 is illustrated. In this arrangement the outer end 60 of the spring 43 is attached to the end of an arcuate adjusting bar 61 concentric 60 with the shaft 42 and having an arcuate slot

for the reception of guiding and retaining screws 62 and 63 which enter threaded openings in the wall of the casing 8. After loosening these screws the bar 61 may be moved endwise, thus varying the tension of 70 the spring.

The operation of the device shown in Figs. 1 to 9 is substantially as follows, it being assumed that when the transmission tube is empty the parts occupy the position shown in Fig. 2 and that at this time a suitable vacuum or low pressure is maintained in the suction tube 7, thus causing a minimum flow of air from the open end 6 of the transmission tube 2 throughout the 80 length of such tube and through the tube 4 and chambers 11 and 12 to the suction tube 7.

When a carrier is inserted in the transmission tube the minimum flow is cut off or reduced and the pressure in the chamber 11 85 drops due to the withdrawal of air therefrom through the minimum flow orifice or passage. This reduction in pressure in the chamber 11 is sufficient to move the diaphragm 17 to the left until it occupies the 90 position shown in Fig. 3. During the early part of this movement the port 23 is open thus permitting atmospheric pressure to act freely upon the right hand side of the diaphragm 17. As the diaphragm moves to the 95 left the end 40 of the stem 31 pushes the valve 41 over to its open position as indicated in Fig. 3 and near the end of this movement the auxiliary valve 26 is swung up until it closes the port 23. 100

The carrier now takes up its flight through the transmission tube and during its flight the air is gradually sucked out of the chamber 22 through the passage 27 until the pressures at opposite sides of the diaphragm 17 105 are substantially balanced. For the proper operation of the device the needle valve 28 is so set that this balancing of pressure may take place prior to the delivery of the carrier from the tube, and of course the setting of this valve will depend to some extent upon the length of the transmission tube, the condition of the tube and carriers, and the suction maintained by the exhauster. 110

115 As soon as the pressures are substantially balanced upon opposite sides of the diaphragm, the spring 33 returns the diaphragm to its normal position as indicated in Fig. 4, leaving the controlling valve wide open since there is no positive connection 120 between the diaphragm stem and the valve. The valve is now maintained in this open position by the tension of the spring 43, which, as above stated, is so adjusted as to hold the valve in this position during the entire flight of the carrier. However, when the last carrier emerges from the transmission tube a sudden rush of air through the tube ensues and when this rush of air strikes 125 the upper surface of the valve 41 the latter 130

is suddenly swung back to its closed position. The valve is free to swing at this time since the stem 31 has previously been retracted as above described, and when the valve reaches its closed position, it is retained there by the suction on the under side of the valve.

When the diaphragm returns to the position shown in Fig. 4, it tends also to open the auxiliary valve 26, but since the chamber 22 is at this time substantially under suction tube pressure, the atmospheric pressure acting upon the outside of the auxiliary valve 26 holds it firmly against its seat, and as the stem 31 moves to the right the spring 38 is stretched as shown in Fig. 4, thus storing up energy.

After the controlling valve 41 has returned to its seat, as shown in Fig. 5, the chamber 15 is cut off from full suction tube pressure so that the pressure in the chamber 22 then rises by leakage through the passage 28 until the pressures upon opposite sides of the auxiliary valve 26 are so nearly equalized that the stored up energy in the spring 38 is sufficient to open the auxiliary valve 23, thus restoring the parts to their original position.

From consideration of the above operation it will be evident that while the controlling valve 41 is opened positively in response to the pressure change resulting from introduction of a carrier into the tube, it is in no way directly influenced by the return of the actuating pneumatic or diaphragm, and remains fully open until the discharge of the last carrier from the tube, when it is then directly closed by the air rush which takes place at the instant of delivery.

The device illustrated in Fig. 10 operates substantially as above described except that a positive lock is furnished for retaining the controlling valve in closed position. With such an arrangement the tension of the spring 43 may if desired be such as to open the valve without any direct push from the diaphragm stem 31, the latter merely acting to release the latch member 57 from the member 56.

While certain preferred embodiments of the invention have herein been shown by way of example, it is to be understood that various changes in the proportions and arrangements of parts may be made if desired and that equivalent parts may be substituted for those here shown or in some instances that certain parts may be omitted without departing from the spirit of the invention, and further that while the actuating pneumatic has been shown and described as a flexible diaphragm, any other suitable device, for example, a piston, may be substituted therefor.

I claim:

1. Power control apparatus for a pneumatic despatch system of the minimum flow

type having a transmission tube and means for creating carrier propelling air flow therein, said apparatus comprising a normally closed controlling valve, a minimum flow through the tube being permitted when the valve is closed, and a pneumatic for opening the valve in response to reduction in pressure in the transmission tube due to introduction of a carrier therein, said valve closing by the direct action of the air current thereagainst when the carrier is delivered from the tube.

2. Power control apparatus of the minimum flow type having a transmission tube, an exhauster, and a controlling valve for governing carrier impelling air flow through the tube, a minimum flow of air through the tube being permitted when the controlling valve is in closed position, said apparatus comprising a pneumatic responding to pressure reduction in the tube due to introduction of a carrier therein, and by such response opening the valve, the pneumatic being movable back to its normal position independently of the valve, the valve being returned to closed position solely by the action thereagainst of the flowing air current.

3. Power control apparatus for a pneumatic despatch system of the minimum flow type having a transmission tube and means for creating carrier propelling air flow therein, said apparatus comprising a normally closed controlling valve, a minimum flow through the tube being permitted when the valve is closed, and a pneumatic for opening the valve in response to reduction in pressure in the transmission tube due to introduction of a carrier therein, the valve being pivoted adjacent to one edge and when open standing in inclined position with its free edge directed toward the air current, said valve closing by the direct action of the air thereagainst when the carrier is delivered from the tube.

4. Power control apparatus for a pneumatic despatch system of the minimum flow type having a transmission tube and means for creating carrier propelling air flow therein, said apparatus comprising a normally closed controlling valve, a minimum flow through the tube being permitted when the valve is closed, and a pneumatic for opening the valve in response to reduction in pressure in the transmission tube due to introduction of a carrier therein, the valve tending to close in direct response to the air current flowing over its surface, and means independent of the pneumatic for holding the valve open so long as a carrier remains in the tube.

5. Power control apparatus for a pneumatic despatch system of the minimum flow type having a transmission tube and means for creating carrier propelling air flow therein, said apparatus comprising a nor-

- mainly closed controlling valve, a minimum flow through the tube being permitted when the valve is closed, and a pneumatic for opening the valve in response to reduction in pressure in the transmission tube due to introduction of a carrier therein, the valve being pivoted and when open standing with one side inclined to the moving air current, and adjustable stop means for determining the angle of inclination of the open valve, the valve closing by the direct action of the flowing air against its inclined surface.
6. Power control apparatus for a pneumatic despatch system of the minimum flow type having a transmission tube, and an exhauster for creating a carrier impelling air flow through the tube, said apparatus comprising a controlling valve for governing such carrier impelling flow, said valve normally occupying a closed position, a minimum flow of air being permitted when the valve is closed, means responsive to introduction of a carrier into the tube for opening the valve, and independent means for holding the valve open during the flight of the carrier.
7. Power control apparatus for a pneumatic despatch system of the minimum flow type having a transmission tube, and an exhauster for creating a carrier impelling air flow through the tube, said apparatus comprising a controlling valve for governing such carrier impelling flow, said valve normally occupying a closed position, a minimum flow of air being permitted when the valve is closed, means responsive to introduction of a carriage into the tube for opening the valve, and a spring for holding the valve open during the flight of the carrier.
- 40 8. Power control apparatus for a pneumatic despatch system of the minimum flow type having a transmission tube, and an exhauster for creating a carrier impelling air flow through the tube, said apparatus comprising a controlling valve for governing such carrier impelling flow, said valve normally occupying a closed position, a minimum flow of air being permitted when the valve is closed, means responsive to introduction of a carrier into the tube for opening the valve, a spring for holding the valve open during the flight of the carrier, and means for adjusting the spring to vary the force exerted thereby.
- 55 9. Power control apparatus for a pneumatic despatch system of the minimum flow type having a transmission tube and means for creating a carrier impelling air flow through the tube, said apparatus comprising a controlling valve for governing such flow, the controlling valve normally cutting off carrier impelling flow, a minimum flow through the tube normally being permitting, a pneumatic which advances in response to decrease in pressure in the tube due to intro-

duction of a carrier therein and thereby opens the valve, and means independent of the pneumatic for holding the valve open during the flight of the carrier.

10. Power control apparatus for a pneumatic despatch system of the minimum flow type having a transmission tube and means for creating a carrier impelling air flow through the tube, said apparatus comprising a controlling valve for governing such flow, the controlling valve normally cutting off carrier impelling flow, a minimum flow through the tube normally being permitted, a pneumatic which advances in response to decrease in pressure in the tube due to introduction of a carrier therein and thereby opens the valve, the pneumatic retreating substantially to normal position prior to delivery of the carrier, and means for retaining the valve in open position during the flight of the carrier.

11. Power control apparatus for a pneumatic despatch system of the minimum flow type having a transmission tube and means for creating a carrier impelling air flow through the tube, said apparatus comprising a controlling valve for governing such flow, the controlling valve normally cutting off carrier impelling flow, a minimum flow through the tube normally being permitted, a pneumatic which advances in response to decrease in pressure in the tube due to introduction of a carrier therein and thereby opens the valve, the valve when open exposing a surface to the flowing air current such that the valve tends to close, means causing the pneumatic to retreat substantially to normal position during the flight of the carrier, and yielding means for holding the valve in open position during flight of the carrier.

12. Power control apparatus for a pneumatic despatch system of the minimum flow type having a transmission tube and means for creating a carrier impelling air flow through the tube, said apparatus comprising a controlling valve for governing such flow, the controlling valve normally cutting off carrier impelling flow, a minimum flow through the tube normally being permitted, a pneumatic which advances in response to decrease in pressure in the tube due to introduction of a carrier therein and thereby opens the valve, the valve when open standing in such position relatively to the air current that the flowing air tends to close the valve, means for moving the pneumatic back substantially to its normal position prior to delivery of the carrier, and means holding the valve open during flight of the carrier but permitting it to close in response to the sudden rush of air following delivery of the carrier from the tube.

13. Power control apparatus for pneumatic despatch system of the minimum flow

- type having a transmission tube and means for creating a carrier impelling air flow through the tube, said apparatus comprising a controlling valve for governing such flow, 6 the controlling valve normally cutting off carrier impelling flow, a minimum flow through the tube normally being permitted, a pneumatic which advances in response to decrease in pressure in the tube due to introduction of a carrier therein and thereby opens the valve, the valve being pivoted to swing and when open being inclined to the flowing air with its free edge directed toward the air current so that the current tends to close the valve, means causing the pneumatic to retreat prior to delivery of the carrier from the tube, and a spring device for holding the valve open until the carrier is delivered from the tube. 10 14. Power control apparatus for a pneumatic despatch system of the minimum flow type having a transmission tube, means for creating carrier impelling air flow therein, and a controlling valve for governing carrier impelling air flow, a minimum flow of air being permitted when the valve is in closed position, said apparatus comprising a valve actuator having a non-positive engagement with the valve, said actuator when moving in one direction opening the valve and when moving in the opposite direction being ineffective to change the position of the valve. 15 15. Power control apparatus of the minimum flow type having a transmission tube, an exhauster and a controlling valve for governing carrier impelling air flow through the tube, a minimum flow of air through the tube being permitted when the controlling valve is in closed position, said apparatus comprising a pneumatic which moves in one direction in response to introduction of a carrier into the tube and thereby opens the controlling valve, the pneumatic returning to normal position without closing the controlling valve. 20 16. Power control apparatus for a pneumatic despatch system of the minimum flow type having a transmission tube, means for creating carrier impelling air flow therein, and a controlling valve for governing carrier impelling air flow, a minimum flow of air being permitted when the valve is in closed position, said apparatus comprising a valve actuating member, a pneumatic for moving said member in one direction to open the valve, and means for restoring the pneumatic to normal position independently of the valve. 25 17. Power control apparatus of the minimum flow type having a transmission tube, an exhauster and a controlling valve for governing carrier impelling air flow through the tube, a minimum flow of air through the tube being permitted when the controlling valve is in closed position, said apparatus comprising a pneumatic which moves in one direction in response to introduction of a carrier into the tube and thereby opens the controlling valve, the pneumatic returning to normal position without closing the controlling valve. 30 18. Power control apparatus for a pneumatic despatch system of the minimum flow type having a transmission tube, means for creating carrier impelling air flow therein, and a controlling valve for governing carrier impelling air flow, a minimum flow of air being permitted when the valve is in closed position, said apparatus comprising a reciprocating pusher which positively moves the valve as it reciprocates in one direction but which is ineffective to move the valve when it reciprocates in the opposite direction. 35 19. Power control apparatus of the minimum flow type having a transmission tube, an exhauster, and a controlling valve for governing carrier impelling air flow through the tube, a minimum flow of air through the tube being permitted when the controlling valve is in closed position, said apparatus comprising a pneumatic and a valve opener connected to the pneumatic, said valve opener being arranged to engage the controlling valve and to push the valve open as the pneumatic moves in one direction, said valve opener retreating freely from the valve as the pneumatic returns to normal position, leaving the valve open. 40 20. Power control apparatus for a pneumatic despatch system of the minimum flow type having a transmission tube, means for creating carrier impelling air flow therein, and a controlling valve for governing carrier impelling air flow, a minimum flow of air being permitted when the valve is in closed position, said apparatus comprising a reciprocating bar, a pneumatic for moving the bar in one direction, and independent means for moving the bar in the opposite direction, movement of the bar in one direction opening the valve, the bar moving in the opposite direction independently of the valve. 45 21. Power control apparatus of the minimum flow type having a transmission tube, an exhauster, and a controlling valve for governing carrier impelling air flow through the tube, a minimum flow of air through the tube being permitted when the controlling valve is in closed position, said apparatus comprising a pneumatic having a reciprocating stem, the stem being arranged to engage the controlling valve and to open the latter as the diaphragm moves in one direction and to move freely away from said valve as the diaphragm moves in the opposite direction. 50 55 60 65 70 75 80 85 90 95 100 105 110 115 120 125 130

22. Power control apparatus for a pneumatic despatch system of the minimum flow type having a transmission tube, means for creating carrier impelling air flow therein, and a controlling valve for governing carrier impelling air flow, a minimum flow of air being permitted when the valve is in closed position, said apparatus comprising a pneumatic moving in one direction in response to reduction in pressure in the tube due to introduction of a carrier therein, a spring for moving the pneumatic in the opposite direction, and a reciprocable stem for the pneumatic, one end of said stem pressing against the valve for opening the latter as the stem moves in one direction and disengaging the valve as the stem moves in the opposite direction.

23. Power control apparatus for a pneumatic despatch system of the minimum flow type having a transmission tube, means for creating carrier impelling air flow therein, and a controlling valve for governing carrier impelling air flow, a minimum flow of air being permitted when the valve is in closed position, said apparatus comprising a pneumatic responsive to introduction of a carrier into the tube, a valve actuating element connected to the pneumatic and normally engaging the valve, means for adjusting the normal position of said actuating member whereby to hold the valve spaced from its seat to provide a minimum flow passage, and means for restoring the actuating element to normal position, said latter means being ineffective to move the valve.

24. Power control apparatus for a pneumatic despatch system of the vacuum minimum flow type having a transmission tube, an exhauster for creating a carrier propelling air flow through the tube, and a controlling valve for governing such flow through the tube, said controlling valve normally occupying a closed position, a minimum flow of air being permitted when the valve is closed, said apparatus comprising means constantly tending to open the valve, such means being incapable of opening the valve while the transmission tube is empty, and means operative upon introduction of a carrier into the transmission tube for positively opening the valve.

25. Power control apparatus for a pneumatic despatch system of the vacuum minimum flow type having a transmission tube, an exhauster for creating a carrier propelling air flow through the tube, and a controlling valve for governing such flow through the tube, the controlling valve normally occupying a closed position, a minimum flow of air being permitted when the valve is closed, said apparatus comprising means tending to open the valve in opposition to the suction produced by the exhauster, and pneumatic responsive to the

reduction in minimum flow through the tube incident to insertion of a carrier therein for positively opening the valve.

26. Power control apparatus for a pneumatic despatch system of the vacuum minimum flow type having a transmission tube, means for creating a carrier propelling air flow therethrough, and a controlling valve for governing such flow through the tube, a minimum flow being permitted when the valve is in closed position, said apparatus comprising a spring tending to open the valve, the latter normally being in closed position, and means assisting the spring to open the valve when a carrier is introduced into the transmission tube.

27. Power control apparatus for a pneumatic despatch system of the vacuum minimum flow type having a transmission tube, an exhauster for creating a carrier propelling air flow through the tube, and a controlling valve for governing such flow through the tube, the controlling valve normally occupying a closed position, a minimum flow of air being permitted when the valve is closed, said apparatus comprising a spring tending to open the valve in opposition to the suction produced by the exhauster, and a pneumatic responsive to reduction in pressure in the tube due to insertion of a carrier therein for assisting the spring in opening the valve.

28. Power control apparatus for a pneumatic despatch system of the vacuum minimum flow type having a transmission tube, means for creating a carrier propelling air flow therethrough, and a controlling valve for governing such flow through the tube, a minimum flow being permitted when the valve is in closed position, said apparatus comprising retaining means normally holding the valve in closed position, and a pneumatic for releasing the valve from the retaining means.

29. Power control apparatus for a pneumatic despatch system of the vacuum minimum flow type having a transmission tube, means for creating a carrier propelling air flow therethrough, and a controlling valve for governing such flow through the tube, a minimum flow being permitted when the valve is in closed position, said apparatus comprising means tending to open the valve, means normally retaining the valve in closed position, and means for releasing the valve from the retaining means.

30. Power control apparatus for a pneumatic despatch system of the vacuum minimum flow type having a transmission tube, means for creating a carrier propelling air flow therethrough, and a controlling valve for governing such flow through the tube, a minimum flow being permitted when the valve is in closed position, said apparatus comprising means for opening the valve, and

mechanical means normally holding the controlling valve in closed position.

31. Power control apparatus for a pneumatic despatch system of the vacuum minimum flow type having a transmission tube, means for creating a carrier propelling air flow therethrough, and a controlling valve for governing such flow through the tube, a minimum flow being permitted when the valve is in closed position, said apparatus comprising releasable means for latching the controlling valve in closed position.

32. Power control apparatus for a pneumatic despatch system of the vacuum minimum flow type having a transmission tube, means for creating a carrier propelling air flow therethrough, and a controlling valve for governing such flow through the tube, a minimum flow being permitted when the valve is in closed position, said apparatus comprising a latch normally holding the valve in closed position, and means for releasing the latch to allow the valve to open.

33. Power control apparatus for a pneumatic despatch system of the vacuum minimum flow type having a transmission tube, means for creating a carrier propelling air flow therethrough, and a controlling valve for governing such flow through the tube, a minimum flow being permitted when the valve is in closed position, said apparatus comprising a spring latch normally retaining the controlling valve in closed position.

34. Power control apparatus for a pneumatic despatch system of the vacuum minimum flow type having a transmission tube, means for creating a carrier propelling air flow therethrough, and a controlling valve for governing such flow through the tube, a minimum flow being permitted when the valve is in closed position, said apparatus comprising a pneumatic for opening the valve in response to introduction of a carrier into the transmission tube, and latch means normally holding the valve in closed position, said latch means releasing the valve to permit it to open freely after a predetermined movement of the pneumatic.

35. Power control apparatus for a pneumatic despatch system of the vacuum minimum flow type having a transmission tube, means for creating a carrier propelling air flow therethrough, and a controlling valve for governing such flow through the tube, a minimum flow being permitted when the valve is in closed position, said apparatus comprising a latch normally holding the valve in closed position, and means for adjustably determining the force necessary to release the valve from the latch.

36. Power control apparatus for a pneumatic despatch system of the vacuum minimum flow type having a transmission tube, means for creating a carrier propelling air flow therethrough, and a controlling valve

for governing such flow through the tube, a minimum flow being permitted when the valve is in closed position, said apparatus comprising a spring latch normally holding the valve in closed position, and means for adjusting the tension of said spring whereby to determine the force necessary to release the valve from the latch.

37. Power control apparatus for a pneumatic despatch system of the vacuum minimum flow type having a transmission tube, means for creating a carrier propelling air flow therethrough, and a controlling valve for governing such flow through the tube, a minimum flow being permitted when the valve is in closed position, said apparatus comprising a pivotal support for the valve, the valve being provided with a latch engaging toe, and a resilient latch member normally engaging said toe and tending to retain the valve in closed position.

38. Power control apparatus for a pneumatic despatch system of the vacuum minimum flow type having a transmission tube, means for creating a carrier propelling air flow therethrough, and a controlling valve for governing such flow through the tube, a minimum flow being permitted when the valve is in closed position, said apparatus comprising a pivotal support for said valve adjacent to one side of the valve, a latch engaging toe projecting to the opposite side of the pivotal support from the main body of the valve, and a spring latch, the toe of the valve normally engaging the latch at such a point relatively to the pivotal support as to tend to keep the valve in closed position.

39. Power control apparatus for a pneumatic despatch system of the vacuum minimum flow type having a transmission tube, means for creating a carrier propelling air flow therethrough, and a controlling valve for governing such flow through the tube, a minimum flow being permitted when the valve is in closed position, said apparatus comprising a pivotal support for the valve, the main body of the valve when in closed position extending to one side of the vertical plane through the pivotal support, a toe member projecting in the opposite direction from the main body of the valve, and a spring latch normally engaging said toe at a point at the other side of said vertical plane from that at which the main body of the valve is situated thereby tending to retain the valve in closed position.

40. Power control apparatus for a pneumatic despatch system of the vacuum minimum flow type having a transmission tube, means for creating a carrier propelling air flow therethrough, and a controlling valve for governing such flow through the tube, a minimum flow being permitted when the valve is in closed position, said apparatus

comprising means tending to open the valve, releasable latch means normally retaining the valve in closed position, and means for releasing the valve from the retaining means.

- 5 41. Power control apparatus for a pneumatic despatch system of the vacuum minimum flow type having a transmission tube, means for creating a carrier propelling air flow therethrough, and a controlling valve 70 for governing such flow through the tube, a minimum flow being permitted when the valve is in closed position, said apparatus comprising means tending to open the valve, releasable latch means normally retaining the valve in closed position, and a pneumatic responsive to reduction in the minimum flow through the transmission tube and by its response releasing the valve from the retaining means.
- 10 42. Power control apparatus for pneumatic despatch systems of the minimum flow type having a transmission tube, an exhaust 75 exhauster, and a valve for controlling carrier impelling air flow through the tube, said apparatus comprising a casing, a diaphragm dividing said casing into two chambers, one chamber communicating with the transmission tube and the other by means of a port with the outer atmosphere, an auxiliary valve for closing said port, means for transmitting movement of the diaphragm in one direction to the controlling valve, and connections transmitting said movement of the diaphragm to the auxiliary valve to close the latter, said connections permitting the diaphragm to move in the opposite direction without opening the auxiliary valve. 80
- 15 43. Power control apparatus for pneumatic despatch systems of the minimum flow type having a transmission tube, an exhaust 85 exhauster, and a valve for controlling carrier impelling air flow through the tube, said apparatus comprising a casing, a diaphragm dividing said casing into two chambers, one chamber communicating with the transmission tube and the other by means of a port with the outer atmosphere, an auxiliary valve for closing said port, and means for transmitting movement of the diaphragm in one direction to the auxiliary valve but permitting the diaphragm to return to its original position independently of the auxiliary 90 valve.
- 20 44. Power control apparatus for pneumatic despatch system of the minimum flow type having a conduit, means for creating a carrier impelling air flow in the conduit, and a controlling valve for governing carrier impelling flow through the conduit, a minimum flow of air through the conduit being permitted when the valve is in closed position, said apparatus comprising a pneumatic 95 exposed at one side to the pressure in said conduit and normally exposed at its other side to atmospheric pressure, the pneumatic responding to introduction of a carrier into the conduit and in so responding opening the valve, and means actuated by the pneumatic for cutting off the pneumatic from atmospheric pressure when the valve opens, said means keeping the pneumatic cut off from atmospheric pressure until after the pneumatic has been restored to normal position.
- 25 45. Power control apparatus for pneumatic despatch systems of the minimum flow type having a transmission tube, an exhaust 100 exhauster, and a valve for controlling carrier impelling air flow through the tube, said apparatus comprising a casing, a diaphragm dividing said casing into two chambers, one chamber communicating with the transmission tube and the other by means of a port with the outer atmosphere, an auxiliary valve for closing said port, and means actuated by the diaphragm as it moves in one direction to open the controlling valve, and a spring for transmitting motion from said means to the auxiliary valve for closing the latter as the controlling valve opens, the diaphragm returning to normal position prior to closure of the controlling valve, the motion transmitting spring stretching during return movement of the diaphragm and becoming operative to open the auxiliary valve only after the controlling valve has closed. 105

with the outer atmosphere, an auxiliary valve for closing said port, and connections between the diaphragm and auxiliary valve for actuating the latter, said connections comprising a yielding member permitting a full movement of the diaphragm in one direction without moving the auxiliary valve.

45. Power control apparatus for pneumatic despatch systems of the minimum flow type having a transmission tube, an ex- 75 hauster, and a valve for controlling carrier impelling air flow through the tube, said apparatus comprising a casing, a diaphragm dividing said casing into two chambers, one chamber communicating with the transmis- 80 sion tube and the other by means of a port with the outer atmosphere, an auxiliary valve for closing said port, means for transmitting movement of the diaphragm in one direction to the controlling valve, and connections transmitting said movement of the diaphragm to the auxiliary valve to close the latter, said connections permitting the diaphragm to move in the opposite direction without opening the auxiliary valve. 85

46. Power control apparatus for pneumatic despatch systems of the minimum flow type having a transmission tube, an ex- 90 hauster, and a valve for controlling carrier impelling air flow through the tube, said apparatus comprising a casing, a diaphragm dividing said casing into two chambers, one chamber communicating with the transmission tube and the other by means of a port with the outer atmosphere, an auxiliary 95 valve for closing said port, and connections actuated by the diaphragm as it moves in one direction to close said auxiliary valve, said connections including a part which stores up energy as the diaphragm returns to normal position and which opens the auxiliary valve after the diaphragm has fully completed its return movement. 100

47. Power control apparatus for pneumatic despatch systems of the minimum flow type having a transmission tube, an exhaust 110 exhauster, and a valve for controlling carrier impelling air flow through the tube, said apparatus comprising a casing, a diaphragm dividing said casing into two chambers, one chamber communicating with the transmission tube and the other by means of a port with the outer atmosphere, an auxiliary valve for closing said port, means actuatable by the diaphragm as it moves in one direction to open the controlling valve, and a spring for transmitting motion from said means to the auxiliary valve for closing the latter as the controlling valve opens, the diaphragm returning to normal position prior to closure of the controlling valve, the motion transmitting spring stretching during return movement of the diaphragm and becoming operative to open the auxiliary valve only after the controlling valve has closed. 115 120 125 130

48. Power control apparatus for pneumatic despatch systems of the minimum flow type having a transmission tube, an exhauster, and a valve for controlling carrier impelling air flow through the tube, said apparatus comprising a casing, a diaphragm dividing said casing into two chambers, one chamber communicating with the transmission tube and the other by means of a port with the outer atmosphere, an auxiliary valve for closing said port, a stem for the diaphragm, said stem being arranged to open the controlling valve as the diaphragm moves in one direction, a spring for restoring the diaphragm and its stem to normal position independently of the controlling valve, and means including a yielding part connecting the diaphragm stem with the auxiliary valve, said latter means closing the auxiliary valve when the diaphragm moves in one direction but yielding to permit the diaphragm to return to normal position without moving the auxiliary valve.

49. Power control apparatus for pneumatic despatch systems of the minimum flow type having a transmission tube, an exhauster, and a valve for controlling carrier impelling air flow through the tube, said apparatus comprising a casing, a diaphragm dividing said casing into two chambers, one chamber communicating with the transmission tube and the other by means of a port with the outer atmosphere, an auxiliary valve for closing said port, a lever arm carrying said auxiliary valve, and means including a tension spring connecting the lever with the diaphragm.

50. Power control apparatus for pneumatic despatch systems of the minimum flow type having a transmission tube, an exhauster, and a valve for controlling carrier impelling air flow through the tube, said apparatus comprising a casing, a diaphragm dividing said casing into two chambers, one chamber communicating with the transmission tube and the other by means of a port with the outer atmosphere, an auxiliary valve for closing said port, and means for transmitting movement of the diaphragm in one direction to the controlling valve for opening the latter and to the auxiliary valve for closing it, said transmitting means permitting the diaphragm to return to normal position without closing the controlling valve or opening the auxiliary valve.

51. Power control apparatus for pneumatic despatch systems of the minimum flow type having a transmission tube, an exhauster, and a valve for controlling carrier impelling air flow through the tube, said apparatus comprising a casing, a diaphragm dividing said casing into two chambers, one chamber communicating with the transmission tube and the other by means of a port with the outer atmosphere, an auxiliary

valve for closing said port, a valve actuating rod connected to the diaphragm, one end of the rod engaging the valve and opening the latter when the diaphragm moves in one direction, the rod being movable in the opposite direction independently of the controlling valve, a spring tending to return the diaphragm to normal position, and means connecting the auxiliary valve to the valve actuating rod and adapted to close the auxiliary valve when the controlling valve opens, said connecting means yielding when the rod moves in the opposite direction to permit the auxiliary valve to remain closed.

52. Power control apparatus for a pneumatic despatch system of the minimum flow type having a conduit, means for creating a carrier impelling air flow in the conduit, and a controlling valve for governing carrier impelling flow through the conduit, a minimum flow of air through the conduit being permitted when the valve is in closed position, said apparatus comprising a casing divided into two chambers by a movable wall, one of said chambers communicating with the conduit and the other with the outer atmosphere by means of a normally open port, an auxiliary valve for closing said port, a stem connected to the movable wall, the wall moving in response to introduction of a carrier into the tube and by means of its stem pushing the controlling valve open, means connecting the stem to the auxiliary valve to close the latter as the controlling valve is opened, means permitting the pressure upon opposite sides of the movable wall to become substantially balanced prior to delivery of the carrier from the tube, and means operative to restore the movable wall to normal position independently of the controlling valve when such pressures are substantially balanced, the auxiliary valve remaining closed after the movable wall has returned to normal position and until the controlling valve closes.

53. Power control apparatus for pneumatic despatch systems of the minimum flow type having a transmission tube, an exhauster, and a valve for controlling carrier impelling air flow through the tube, said apparatus comprising a casing, a diaphragm dividing said casing into two chambers, one chamber communicating with the transmission tube and the other by means of a port with the outer atmosphere, an auxiliary valve for closing said port, means providing a passage leading from one of said chambers to the other, a valve actuating rod connected to the diaphragm, a spring tending to maintain the rod in inoperative position, and means connecting the rod to the auxiliary valve, the diaphragm responding to introduction of a carrier into the transmission tube and thereby moving the actuating rod

- to push open the controlling valve and close the auxiliary valve, the passage between the chambers being of such capacity that after the controlling valve opens the pressure in the two chambers is substantially equalized prior to delivery of the carrier from the tube, the spring then returning the actuating rod to normal position leaving the controlling valve open.
- 10 54. Power control apparatus for pneumatic despatch systems of the minimum flow type having a transmission tube, an exhauster, and a valve for controlling carrier impelling air flow through the tube, said apparatus comprising a casing, a diaphragm dividing said casing into two chambers, one chamber communicating with the transmission tube and the other by means of a port with the outer atmosphere, the casing having a passage connecting said chambers, an adjustable bleeder valve controlling said passage, an auxiliary valve for closing the port leading to the atmosphere, a valve actuating rod connected to the diaphragm, one end of the rod being disposed adjacent to 25 the surface of the controlling valve, means including a yielding element connecting the rod to the auxiliary valve, a spring tending to hold the rod in normal position, and means tending to hold the auxiliary valve in 30 open position, the diaphragm responding to introduction of a carrier into the tube and thereby moving the rod to push the controlling valve open and to close the auxiliary 35 valve, the bleeder valve being so set that after the controlling valve opens and before the carrier is delivered the pressure in the two chambers are substantially equalized whereby the diaphragm and rod return to normal position, the controlling valve remaining open, and the yielding connection 40 permitting the auxiliary valve to remain closed until the carrier is delivered from the tube.
